UNITED STATES PATENT OFFICE.

SILAS I. ATWATER, OF NEW YORK, N. Y.

CHANGEABLE CHARACTER, REVERSIBLE SIGN.

Application filed January 6, 1922. Serial No. 527,374.

To all whom it may concern:

Be it known that I, SILAS I. ATWATER, a citizen of the United States, residing in New York, in the county of New York and State 5 of New York, have invented certain new and useful Improvements in Changeable Characters, Reversible Signs, of which the following is a specification.

One of the objects of the invention is to 10 provide a sign having elements of construction whereby plates bearing imprinted characters may be resiliently engaged between spring retaining bars arranged longitudinally of a frame.

Another object is in the means provided 15 by which a plurality of spring bars are held in vertical arrangement by tensional locking strips adjacent the upper edges of the bars.

A further object is in the provision of 20 means whereby a number of relatively short spring bars may be arranged to abut at their ends, thus forming, continuous bar of indefinite length and held from sectional 25 arrangement by locking strips of comparatively short lengths, tensionally engaging the spring bars in staggered or broken joint relation, when a plurality of the sectional bar and strip elements are arranged in vertical 30 order.

A still further object is in the provision of a removable letter sign that is fully reversible and adapted for use on both sides and which presents a built-up surface that 35 requires no cross bars as are usually employed for stiffening and covering joints of removable letter signs.

These and other objects which will appear 40 are attained by the novel construction, combination and arrangement of parts herein-after described, and shown in the accompanying drawing, forming a material part of this disclosure and in which:—

Figure 1 is a perspective view of a sign 45 made in accordance with the invention.

Figure 2 is a vertical sectional view of the same.

Figure 3 is an enlarged fragmental perspective and sectional view showing the arrangement of adjacent members.

Figure 4 is a perspective view of one of the character plates.

Figure 5 is a transverse sectional view of the spring bars and locking strips having 55 modified lower end elements.

Referring in detail to the drawings, the numeral 10 designates generally an oblong rectangular frame, having top and bottom elements 11 and 12, and end elements 13 and 14 respectively.

A rabbet or groove 15 is formed in the inner surfaces, centrally of the four sides of the frame, those in the top and bottom elements being adapted to receive grooved channel bars 16, and the grooves in the side 65 elements to receive the extreme ends of the spring bars and locking strips as later described.

The channel bars 16 are suited in length to the frame and consist of metal strips having flanged parallel extending sides 16' adapted to fit into the grooves 15 of the frame members 11 and 12, and depressions 17 are formed centrally and longitudinally in the exposed main surfaces of the bars.

V-shaped spring bars 18 are formed from strips folded angularly, centrally of their width, as at 19 in Figure 3, the free, separated upper portions being bent inward forming curved corner edges 20, and continuing angularly downward into flanged shoulders 21, their inner, adjacent edges being in register and held in close proximity by the tensional pull of the fold 19.

These edges are adapted to be forced 85 slightly apart by a rib 22, formed on the under side, centrally and longitudinally of a locking strip 24, of corresponding length and having angularly and oppositely disposed wing elements 25 to engage over the 90 flanges 21 and resiliently seat thereon.

Metal plates 26 are bent at their upper ends, the curves terminating in angular extensions 27, adapted to be entered and resiliently secured between the elements 21 and 95 25 of the bars and locking strips 18 and 24 respectively.

These plates 26 bear upon their front surfaces characters, such as the letters of the alphabet, figures, etc., and may be made in 100 any desired width and length.

In Figure 5 is shown a modification of the spring bars 28, in which the same are separated at the lower angularly converging part of the bar instead of the upper, wider 105 portion as previously described and an arcuate groove 29 is found centrally in the upper element of the bar, to receive the rib element 22 of the locking bar.

The locking strip 30 is formed as before 110

described and adapted to engage and resiliently close the opening 29 between the abutting edges of the spring bar 28.

Constructionally, the spring bars 18 and 5 the locking strips 24, when used in relatively small signs are preferably made as single units, while in signs of greater length, the spring bars are made up of comparatively short lengths 18, whose ends abut one another, as at 32, and these sections are held rigidly in longitudinal alinement by means of short lengths 24 of the locking strips, which are arranged as to break joints with the spring bar sections.

15 It will be apparent that any number of bars may be employed as may be desired to build-up signs of any required height.

It is also evident that the character plates may be applied to either or to both sides of 20 the sign, and that the frame may be inverted and even roughly handled without danger of displacing the sign plates.

As previously mentioned, the bar and strip elements extend beyond the interior length 25 of the frame members and are entered into the grooved rabbets formed in the end members of the frame.

While certain preferred embodiments of 30 this device have been shown and described, it will be understood that changes in the form, arrangements, proportions, sizes and details thereof may be made without departing from the scope of the invention as defined in the appended claims.

35 Having thus described my invention, what I claim as new and desire to secure by Letter Patent, is:—

1. A sign comprising a plurality of bars, supports therefor, character bearing plates 40 engageable selectively with any of said bars upon either side thereof, and resilient strips interposed between said bars for clamping said plates to said bars.

2. A sign comprising a plurality of V 45 shaped bars having inturned flanges on their upper edges, character plates having angularly bent upper edges adapted to be disposed over said flanges, and a spring rail normally in contact with said flanges adapted 50 to clamp the entered edge of each character plate.

3. A sign comprising a frame having 55 grooves in its inner surfaces, channel bars disposed in the grooves of the upper and lower frame members, hollow symmetrical

bars of triangular cross section having their ends disposed in the grooves of the end members of said frame, flanges extending from the upper, wider portion of said bars, said flanges presenting open spaces, strips 60 equal in width to the widest portion of said bars, said strips being shaped to rest on said flanges, continuous beads formed centrally of said strips adapted to enter the mentioned spaces, independent character 65 carrying plates, and flanges formed at the upper extremities of said plates adapted to be inserted between the flanges of said bars and the laterally extending portion of said strips at either side thereof.

4. A changeable letter sign comprising a rabbeted frame, a plurality of one piece spring bars longitudinally disposed and arranged vertically one above the other said bars being secured at their ends within the 75 side rabbets of said frame, locking strips interposed between said spring bars and interchangeable sign letters resiliently engageable between said spring bars and the adjacent locking strips.

5. A changeable letter sign having a rabbeted frame, V shaped spring bars having spaced inturned upper portions, locking strips engaged in the mentioned spaces said strips consisting of narrow oblong rectangular plates bent along the center to form an obtuse angle in section conformable with the inturned edges of the spring bars, an arcuate rib formed from the apex of said obtuse angle; means for tensional holding 90 said rib within said slot, and means on the opposite side of said locking plate for engaging an adjacent spring bar.

6. A changeable letter sign comprising a plurality of character carrying plates, a rabbeted frame, a plurality of spring bars disposed longitudinally of the frame and composed of one or more units of comparative short length abutting at their ends, locking strips engageable with said spring 100 bars and of lengths adapted to break joints with said spring bars, said locking strips and spring bars being arranged one above the other to present means between the strips and bar members for holding said character 105 carrying plates.

In testimony whereof I have signed my name to this application.

SILAS I. ATWATER.
